(57) **CLAIM**

The ornamental design for an electronic payment device, as shown and described.

DESCRIPTION

FIG. 1 is a top perspective view of an electronic payment device in accordance with the present design;

FIG. 2 is a bottom perspective view thereof;

FIG. 3 is a front view thereof;

FIG. 4 is a bottom view thereof;

FIG. 5 is a left side view thereof;

FIG. 6 is a right side view thereof;

FIG. 7 is a top view thereof;

FIG. 8 is a back view thereof;

FIG. 9 is a top perspective view of an electronic payment device in accordance with the present design;

FIG. 10 is a bottom perspective view thereof;

FIG. 11 is a front view thereof;

FIG. 12 is a bottom view thereof;

FIG. 13 is a left side view thereof;

FIG. 14 is a right side view thereof;

FIG. 15 is a top view thereof;

FIG. 16 is a back view thereof;

FIG. 17 is a top perspective view of an electronic payment device in accordance with the present design;

FIG. 18 is a bottom perspective view thereof;

FIG. 19 is a front view thereof;

FIG. 20 is a bottom view thereof;

FIG. 21 is a left side view thereof;

FIG. 22 is a right side view thereof;

FIG. 23 is a top view thereof; and,

FIG. 24 is a back view thereof.

The broken lines in the drawing figures depict unclaimed environment and form no part of the claimed design.
